UNITED STATES PATENT OFFICE.

JOHN E. BIRCH, OF WINNIPEG, MANITOBA, CANADA, ASSIGNOR OF ONE-HALF TO DONALD HENDERSON, OF SAME PLACE.

AUTOMATIC CUT-OFF FOR GAS-BURNERS.

SPECIFICATION forming part of Letters Patent No. 326,832, dated September 22, 1885.

Application filed February 24, 1885. (No model.)

To all whom it may concern:

Be it known that I, JOHN EDWARD BIRCH, a subject of the Crown of Great Britain, residing at Winnipeg, Manitoba, Canada, have 5 invented certain new and useful Improvements in Automatic Cut-Offs for Gas-Burners, of which the following is a description.

Figure 1 is a vertical central section showing the parts in the position which they assume just as the illuminating-jet is about to be ignited. Fig. 2 is a sectional view showing the opening of the valve *k* by the excessive rise of cylinder *h*.

The object of my invention is to provide a 15 gas-burner which will automatically cut off its flow of gas whenever the flame from any cause becomes extinguished. Sometimes when water or air gets into the gas-pipes the flame will become extinguished, and the gas will continue to flow into the room and involve the 20 risk of poisoning the sleeping occupants; or in some hotels, where the gas is cut off at the meter at night and turned on again in the morning, gas which has been left burning in 25 an apartment will commence to flow through the open cocks and involve serious consequences to persons who may have fallen asleep with the gas turned on. Ignorant persons, too, 30 frequently incur the same risk by blowing out the gas and retiring.

My invention is designed to obviate the dangerous consequences of such contingencies by means of a gas-burner which is self-closing when the flame is extinguished, and for which 35 purpose I make use of the expansibility of a confined body of air, which, when expanded by the normal heat of the burner, holds open a valve that permits the flow of gas to continue, and which body of air when cooled by the 40 extinguishment of the flame contracts and closes the valve, thus cutting off the flow by a positive and certain action. My invention consists in the peculiar construction and arrangement 45 of parts operating on this principle, as will be hereinafter more fully described.

In the drawings, *a* represents the outer case of the burner, which may be of any approved shape, and which at its lower end is screw-threaded, as at *b*, to permit it to be screwed in 50 the usual way to the threaded nipple of the gas-bracket. The upper end of this case is

enlarged at *c*, and screw-threaded interiorly to fit an external screw-thread of a cap, *c*, which closes the upper end of the case, and has a central nipple to receive the ordinary lava or 55 metal tip, *d*. Upon the shoulder of the lower part of the section *e* is sustained a cylindrical air cell or pocket, *f*, made of metal, and having a flange, *i*, at its top, by which it is sustained in central position in the case, which cell is 60 closed at the bottom and open at the top. This flange *i* has a series of small holes, *o*, through it that communicate below with the annular gas-space between the outer case and the air-cell, and with the gas-space beneath cap *c* 65 above, which holes form conduits or passages through which the gas reaches the top of the burner. Within the air-cell *f* a closely-fitted cylinder, *h*, is arranged, which is closed at its upper end, and is provided with a flange that 70 overhangs the perforated flange of the air-cell, and forms a gas-valve, as hereinafter described. The lower portion of this cylinder is immersed in a mercury-seal contained in the cell *f*, and thus imprisons a body of air in said cylinder. 75

The normal operation of this burner is as follows: The air within the cylinder *h* is expanded by the heat of the burner, and raising cylinder *h* lifts its flange off the holes *o* in the flange of the air-cell, and allows gas to pass 80 from the annular space around said air-cell up to the tip of the burner, which condition of things is maintained as long as the flame of the burner continues. As soon, however, as the flame is extinguished the air within the cylinder *h* cools, and in contracting allows the cylinder to drop down into the mercury, and brings the flange of the said cylinder tightly 85 down upon the holes *o*, which admit gas to the top, thus automatically cutting off the supply 90 of gas. To avoid the necessity of using so much mercury, a tube or post, *g*, is placed in the center of the air-cells, and acts as a displacing body to maintain the height of the 95 mercury and reduce its bulk.

To open the cylinder-valve and allow the gas to issue in first lighting, a supplemental jet is provided by a nipple, *n*, in which plays a short stem having a valve, *r*, on the inside, and a push-button, *s*, on the outside, provided with 100 suitable packing-washers, and around this stem a spiral spring is coiled. By pushing

button *s* in, as shown, by the finger, valve *r* is opened, and a jet of gas is allowed to issue, which being ignited heats the air in cylinder *h*, and this body of air in expanding lifts the flange-valve at the top of the cylinder, which allows the gas to issue through the tip *d*, which gas is immediately ignited from the lower supplemental jet. After this the pressure on button *s* is discontinued, and the air in cylinder *h* is kept expanded by the heat of the gas-jet at *d*. If the heat of the burner is so great as to produce an undue expansion of the air and excessive elevation of the cylinder *h*, a valve, *k*, is made to open in the top of the cylinder automatically and allow some of the air to escape. This is effected as follows: A screw-threaded adjusting-bar, *m*, on the stem of valve *k* strikes the cap *c* as cylinder *h* rises too high (see Fig. 2) and forces the valve down against the tension of bow-spring *l*, thus opening the valve and allowing it to be closed again when the excessive expansion has been relieved.

To regulate or vary the flow of gas through holes *o* in flange *i*, a ring, *j*, with corresponding holes, is placed beneath the flange, and is turned at will to cut off more or less of the gas passing through.

Having thus described my invention, what I claim as new is—

- 30 1. An automatic cut-off burner consisting of an outer gas-chamber provided with a tip, an expandible air-chamber located therein, and formed of two parts sealed with mercury, one of said parts being provided with a flange, and the other with a set of holes to constitute with said flange a valve which is opened and closed by the expansion and contraction of the air within the air-chamber, substantially as described.
- 40 2. In an automatic cut-off burner, the combination, with a gas-burner, of a valve provided with an expandible air-chamber, and a supplemental jet in close proximity to the burner and air-chamber, whereby the lighting of said supplemental jet will produce the initial expansion of air and start a flow of gas through the burner and ignite the illuminating-jet, substantially as described.
- 45 3. In an automatic cut-off burner, the com-

bination, with a gas-burner, of a gas-valve connected to the movable part of an expandible air-chamber, an escape-valve located in the movable part of the expandible air-chamber, and having an operating-arm extending to a point near the gas-burner, whereby it will be operated by an undue expansion of the air in said chamber by contact with the burner, as set forth.

4. The combination of the outer case, *a*, the flanged and suspended air-cell *f*, containing mercury in its bottom, and having gas-holes *o* in its flange, and the rising and falling cylinder *h*, having a close top and flange-valve overhanging the gas-holes *o*, and having its lower end sealed in the mercury, as shown and described.

5. The combination of case *a*, having an enlarged screw-threaded upper section, *e*, the screw-threaded cap *c*, with tip-socket, and tip *d*, the flanged air-cell *f*, having perforated sustaining-flange *i*, the rising and falling air-cylinder *h*, having flange-valve at the top, and the mercury-seal at the bottom, substantially as shown and described.

6. The combination, with the inclosing-shell *a* *c*, and the air-cell *f*, of the rising and falling air-cylinder *h*, having a gas-valve attached thereto, and the valve *k*, and valve-stem provided with spring *l*, and nut or holding-bar *m*, as and for the purpose described.

7. The combination, with case *a*, having an enlarged shoulder section, *e*, of the air-cell *f*, having flange *i*, with gas-holes *o*, and the regulator or adjusting-ring *j*, having similar holes laid between the flange of the air-cell and the shoulder of the case, and made axially adjustable to increase or diminish the flow of gas at will, substantially as described.

8. The combination, with the gas-burner having a pneumatic cut-off, of the nipple *n*, the stem having valve *r* at one end and push-button *s* at the other, and the coil-spring surrounding said stem, substantially as and for the purpose described.
